UNITED STATES PATENT OFFICE.

WILLIAM HARDING SCOTT, OF NORWICH, ENGLAND.

REGULATOR FOR USE IN CHARGING ACCUMULATOR-CELLS FOR MOTOR-CAR LIGHTING AND STARTING AND FOR SIMILAR PURPOSES.

1,191,129.

Specification of Letters Patent. Patented July 11, 1916.

Application filed June 22, 1914. Serial No. 846,586.

To all whom it may concern:

Be it known that I, WILLIAM HARDING SCOTT, a subject of the King of Great Britain, residing at Gothic Works, Norwich, England, have invented new and useful Improvements in Regulators for Use in Charging Accumulator-Cells for Motor-Car Lighting and Starting and for Similar Purposes, of which the following is a specification.

10 My invention relates to the known regulators in which in the shunt circuit of a generator used for charging a secondary battery, a number of carbon blocks, or disks, are employed, the said blocks, or disks, being normally pressed together with a moderate pressure applied by a weight acting in opposition to which is an electro-magnet, acting upon an armature as to tend to relieve the carbon blocks, or disks, from the 15 pressure exercised upon them by the aforesaid weight. In such regulators it has been proposed to use a fixed resistance across the ends of the series of carbon blocks, or disks, with the object of not allowing all the 20 current to pass through the carbon blocks, or disks, while leaving them capable of maintaining the voltage. I make no general claim to regulators constructed on the foregoing principle.

25 According to my invention I make the aforesaid armature of the electro-magnet a lever, which turns on a knife-edge fulcrum, which forms part of the magnetic circuit, the aforesaid short ranged spring, or the 30 equivalent, being arranged to act on one arm of the said lever to exert pressure on the carbon blocks, or disks, the electro-magnet, when energized, operating on the other arm of the said lever in opposition to the said 35 spring.

40 Figure 1 of the accompanying drawings represents, a device constructed in accordance with this invention, and Fig. 2 is a diagram illustrating its application to the shunt circuit of a generator.

45 In the shunt circuit A, of the generator B, are the carbon blocks, or disks, C, inclosed in an insulating tube D mounted in carriers E which can be insulated from the base plate F. The said carbon blocks, or disks, are normally pressed together with a moder-

ate pressure by means of the short-ranged spring G, acting in opposition to which is the electro-magnet H, the winding of which is illustrated as being a series winding, but any other suitable winding may be employed. When the conditions are such that the resistance through the regulator is to be increased the said magnet will be energized so as to act upon the armature I against the pressure exercised by the spring G and relieve the carbon blocks, or disks, C from such pressure, or lessen it.

50 J, Fig. 2 indicates the aforesaid fixed resistance across the ends of the series of carbon blocks, or disks. This resistance J, is not seen in Fig. 1.

The armature I of the electro-magnet H turns on a knife edge i which forms part of the magnetic circuit, the spring G being arranged to act on the arm i' of the armature I, to exert the required pressure on the carbon blocks, or disks, C while the electro-magnet I when energized, acts on the other arm i'' of the said armature in opposition to the said 75 spring G. The pressure of the spring G is conveyed to the carbon blocks, or disks, C by a sliding stem K and at the other end of the series of blocks, or disks, C is a screw L by which the minimum resistance can be 80 regulated and its degree indicated by a pointer l.

85 By inclosing the carbon blocks, or disks, in an insulating container which is air-tight, or practically so, the rate of burning away when arcing takes place between the carbon blocks, or disks, is reduced, the resistance J, further reducing this arcing.

What I claim is:—

1. In regulators of the character described, a series of carbon blocks, an armature lever having an operative bearing on said blocks, a spring acting in one direction upon said lever and an electromagnet acting in the opposite direction thereon, and an 95 armature supporting arm having a knife edge support for the armature in the magnetic circuit.

2. In regulators of the character described, a series of carbon blocks, an armature lever having an operative bearing on said blocks, a spring acting in one direction 100

upon said lever and an electromagnet acting in the opposite direction thereon, said electro-magnet having a branch arm in the magnetic circuit and provided with a knife edge forming a support for the armature, substantially as described.

In testimony whereof I have signed my

name to this specification in the presence of two subscribing witnesses.

WILLIAM HARDING SCOTT.
